UNITED STATES PATENT OFFICE

ARNOLD A. STEPHENS, OF DAVENPORT, IOWA

HOLLOW PISTON

Application filed November 23, 1928. Serial No. 150,307.

This invention relates to engine pistons and more particularly to pistons of non-ferrous metals or alloys.

It has been proposed heretofore to construct pistons of aluminum. The relative light weight of this metal makes it desirable for such a use. Such pistons, however, have not given satisfactory service. Due to its high coefficient of thermal expansion, it was necessary to allow a relatively large initial clearance between the piston and the cylinder bore. Decided disadvantages resulted from this, such as accentuated piston slap and excessive cylinder wall wear.

To improve the efficiency of such aluminum pistons it was suggested to make the skirt of a relatively large diameter and to provide it with splits, so that the whole skirt could compress as the material expanded due to the high temperatures obtaining within the cylinder.

In the ordinary constructions of pistons embodying this feature, the skirt is cut away at that portion between the oil ring and wrist pin bosses. The use of this design of piston is attended by serious disadvantages. The cut away portion causes a break in the heat conducting path from the head to the skirt and concentrates heat at the bearings, thereby causing distortion on these stressed parts. In addition, this cut away portion lowers the actual bearing surface of the piston which results in vibration of the piston head and consequent heavy wear.

It is an object of my invention to provide a piston of light weight in which lateral motion is reduced to a minimum.

Another object is to provide a piston which has a high bearing surface.

A further object is to provide a piston which dissipates heat effectively.

Yet another object is to provide a piston of a light metallic material of simplified structure which may operate with a minimum of clearance.

I accomplish the foregoing and other important and related objects by constructing a piston of a metal or metallic alloy of low specific gravity and having a rigid head and compressible skirt and fitted with a high bearing section preferably of a metal of a higher specific gravity than the metal of the piston proper.

To make my invention more clearly understood I have shown in the accompanying drawings a practical embodiment which comprehends its salient features and in which like reference numerals refer to similar parts throughout the several figures, of which,

Figure 1 is a side elevation of the piston mounted in a cylinder;

Fig. 2 is an elevation taken at a right angle to the view of Fig. 1;

Fig. 3 is a section on the line 3—3 of Fig. 2;

Fig. 4 is a detail view of a portion of the device shown in Fig. 3.

In Fig. 1 there is shown a cylinder 1 enclosed by a water jacketed engine block 2 and cylinder head 3. Within the cylinder there is mounted a piston 4. The piston is connected to an engine shaft through the intermediacy of a connecting rod 5, wrist pin 6 and wrist pin bushings 7 in the conventional manner.

The piston may be composed of a metal or metallic alloy having a low specific gravity as compared to iron. I prefer to construct the piston of a fine grained aluminum material, either aluminum or an alloy of aluminum having the requisite strength for this use.

The piston comprises a head portion 4 and a skirt section 5. The head is truly circular and is provided with a plurality of grooves. One group of grooves may be of the same size to receive the piston rings 8 and 9 and the oil ring 10. The other groove 11, shown particularly in Fig. 3, is of much greater height than the compression ring grooves and is adapted to seat a bearing member 12, to be more fully described hereinafter.

The skirt portion as initially formed com-

prises a plurality of integral cylindrical sections. On the thrust side of the piston the skirt is formed with a quadrantal cylindrical section 13 which has a greater radius than 5 the remaining cylindrical section, as described in my copending application Serial No. 101,940. At the side opposite the thrust side the skirt is split as at 14. As shown, particularly in Fig. 2, this is a Y-shaped cleft 10 although it is to be understood that I may use a single or any desired type of split.

It will now be seen that the lower portion 15 of the skirt, and more especially that section subtended by the V-shaped split 14 and adjacent the vertical split 14 will tend to spring out or expand. These portions will bear 20 against the cylinder bore and serve to restrict lateral movement of the lower part of the piston. As the piston becomes heated, this 25 aluminous material will expand considerably because of its relatively high thermal expansion. By constructing the piston as described there is provided, in effect, an expansible and contractible skirt. In the early running 30 stages, when the piston is relatively cool, the expanded lower section of the skirt presents too great a clearance between the cylinder and piston. As the piston becomes heated the lower part of the skirt will expand and tend 35 to press against the cylinder bore. Should the skirt expand beyond the minimum clearance the ends adjacent the vertical split will approach each other, due to pressure exerted by the cylinder wall. Thus the danger of seizing is eliminated.

As intimated hereinbefore, in the usual 40 aluminum piston construction the skirt is cut away for a portion of its length between the wrist pin bosses and the oil ring. In addition to causing distortion of the wrist pin bosses and allowing vibration of the piston head, this method of construction weakens an 45 aluminum piston considerably.

I find that these undesirable effects can be 50 obviated by providing a separate bearing surface in the piston head. I accomplish this by placing in the head an annular section of metal of a coefficient of expansion approximating that of the metal of the cylinder.

55 As shown in Fig. 3, this auxiliary head section comprises an annular split ring 12. Because of its cheapness and its thermal expansion coefficient, I prefer to use iron. This member, while carried by the head, is contractible independently of the head. Positioned intermediate the ring and the bottom of its cooperating groove is a polygonal spring 16. This resilient member conforms in circumferential length to that of the section of that skirt of smaller diameter. Seated 60 in the groove between the free ends of the spring is a filler block 17. The ring 12 is maintained in circular form by the cooperating action of the spring and filler block.

65 To prevent unrestricted action of the

spring, I have provided a means for limiting its expansion. This comprises a supporting base 18 which is of the same curvature as the groove bottom and filler block. Integrally formed with the supporting base and intermediate its ends is a tenon 19. On its other side, at each end, the base is formed with integral extending undercut pins 20. These pins are adapted to register with the channels 21 cut in the interior periphery of the ring. It will be noted that the channels are considerably wider than the locking pins and hence the ring may expand and contract through a limited range. It is to be understood that the filler block is of appropriately reduced width at that portion which abuts the plate 18. The tenon 19 is seated in a recess in the filler block. This effectively anchors the plate 18 and filler block against circumferential movement in the groove. While I have shown the filler block and locking plate as separate pieces, it will be appreciated that I may provide ring locking pins on the filler block itself and anchor this to the piston by any suitable means.

70 The operation of the bearing ring will be apparent from the foregoing description. The spring 16 will tend to expand the ring to the limit allowed by the locking means, that is until the edges of the undercut pins 80 abut the sides of the channel adjacent the angular split. The spring forces the ring 85 away towards the side opposite the thrust side and hence maintains the ring in close contact with the filler block and supporting 90 base.

95 When the piston is inserted in the cylinder bore, the ring may bear against the adjacent cylinder wall. As it is run in, a glazed surface is worn on the ring and a small clearance 100 between the ring and cylinder is insured. It will now be appreciated that the piston head is in effect that of cast iron in respect of cylinder clearance. Due to the provision of the resilient member and allowance of movement of the bearing ring the aluminous material of the head may expand or contract 105 independently of the auxiliary iron head section. The contractibility of the ring precludes the possibility of seizing, since this member can exert a pressure against the cylinder bore only equal to the expansive force 110 of the spring.

115 By providing a high bearing surface in conjunction with a contractible skirt portion, bodily lateral movement and oscillation about the wrist pin is minimized. This structure in addition enables the construction of a full cylindrical piston and this insures the maximum strength.

120 A piston constructed in accordance with this design dissipates heat generated in the cylinder head most effectively. A continuous heat conducting path from the head to the skirt is provided. This, as has been pointed 125

out, prevents concentration of heat at the wrist pin bosses and thus eliminates the danger of distortion of these parts. This piston combines the advantages of the light 5 weight of aluminum with the desirable clearance features of cast iron. The device is of simple construction comprising but few easily assembled and replaceable parts.

While I have shown and described a preferred embodiment of the invention, it is to 10 be understood that this is given but as an example of one way in which the underlying features of the invention may be incorporated in a mechanical structure, for since the invention 15 is susceptible of other mechanical embodiments, I do not intend to be restricted to any particular structure except as such limitations are imposed in the appended claims.

I claim:

20 1. A hollow piston comprising a rigid head and resilient skirt portion, a split contractible and expandible bearing member in the head having less thermal expansion than the material of the piston and means to limit the expansion 25 of the bearing member.

2. A hollow piston comprising a rigid head and a resilient skirt portion, a separate substantially freely contractible and expandible section in the head of a different material 30 from that of the head and skirt expandible and contractible independently of the head.

3. A hollow piston comprising a head and split skirt portion of a metal having a relatively low specific gravity, compression rings 35 in the head, a separate substantially freely expandible and contractible head section of a metal of a lower degree of thermal expansion than the metal of the head and skirt and means cooperating with the head and the 40 head section to limit the expansion of the head section.

4. A piston of the character described comprising a rigid head provided with compression rings, a full cylindrical split skirt integrally formed with the head, the head and skirt being formed of a metal of relatively low specific gravity, a separate split head section of a material having a lower degree 50 of thermal expansion than the metal of the head and skirt and means to limit the expansion of the head section.

5. A piston of the character described comprising a head and a split skirt forming a continuous cylindrical surface with the head, the head and skirt being formed of a material of relatively low specific gravity and relatively high degree of thermal expansion, a separate annular section mounted in the head 60 expandible and substantially freely contractible independently of the head, said section being formed of a material of greater specific gravity and of smaller degree of thermal expansion than the metal of the head and skirt.

6. A piston comprising a head and resilient skirt of an aluminous material, compression

rings carried by the head, a separate annular head section of ferruginous material expandible and contractible independently of the head and means cooperating with the head and said section to limit the expansion 70 of the latter.

7. A piston comprising a head and skirt of aluminous material, compression rings carried by the head, a separate annular head section of a ferruginous material provided with 75 means to limit its expansion and permit substantially free construction, the skirt section being split at one side and at the opposite side being formed with an extended segment.

8. A piston comprising a head and resilient skirt of an aluminous material, compression rings carried by the head, a separate annular expandible head section of a ferruginous material and means to limit the expansion and permit substantially free contraction 85 of said section including under cut pins supported by the head and engaging the section.

9. A piston comprising a rigid head and a split skirt of a metal having a relatively low specific gravity, a spaced head section expandible and substantially freely contractible independently of the piston head and of a material having a greater specific gravity than the piston, means carried by the head to limit the expansion of the section. 95

10. A piston comprising a head and skirt of a material having a specific gravity less than iron, a separate annular expandible section of ferruginous material mounted in the head, and means to restrain the expansion 100 of the section comprising a curved plate having oppositely projecting members adapted to secure the plate to the piston and to restrain the expansion of the section.

11. A restraining means of the character 105 described comprising a plate having oppositely projecting central and end extensions.

12. A piston comprising a body portion of a material having a specific gravity less than iron, a separate annular radially expandible 110 section formed with grooves in its interior face, and means detachably secured to the piston body and slidably engaging the grooves to restrain expansion of the section.

13. A piston comprising a head provided 115 with compression rings, a skirt, an expandible annular section mounted in a groove in the piston, means detachably seated in the groove to limit the expansion of the section and to transmit the thrust of the piston directly to 120 the section.

14. A piston comprising a body portion of an aluminous material, a separate annular expandible section maintained in the piston, and means to limit the expansion of the section comprising a single piece of metal having spaced angularly projecting arms and engaging the section to limit its expansion, and a second oppositely extending projection for connection with the piston body. 125

15. A piston having a head and skirt, a plurality of compression rings and an oil ring carried in grooves in the head, a split bearing ring of greater width than the compression rings supported in a groove positioned above the oil ring, a resilient member interposed between the bearing ring and the bottom of its cooperating groove, and means coacting with the bearing ring adjacent the split thereof to limit the expansion of said bearing ring.

In testimony whereof I affix my signature.

ARNOLD A. STEPHENS.
